GEORGE E. GIBSON, OF UPPER MONTCLAIR, NEW JERSEY

COMBUSTION CONTROL

Application filed May 9, 1928. Serial No. 276,278.

My present invention comprises improvements in methods of and apparatus for the automatic control of combustion conditions in furnaces and particularly in boiler furnaces, devised with the general object of providing a control system for a boiler furnace characterized by its effectiveness and operative simplicity and by its capacity for the attainment of specific objects hereinafter set forth.

A more specific object of the invention is to provide a boiler furnace combustion control system of the type in which combustion controlling factors in the different boiler furnaces are adjusted in proportion to changes in a primary control force, with improved means for so establishing and adjusting said control force as to tend to maintain an approximately constant header steam pressure as the demand for steam varies, notwithstanding the variations in the drop in steam pressure at different rates of steam output between the steam generating boiler or boilers of the system and the steam header due to changes in steam velocity and frictional resistance in the pipe connections through which steam passes from the boiler or boilers to the header.

Another specific object of the invention is to subject the combustion control system to means responsive to certain water conditions in the boiler or boilers of the system for the purpose of reducing the heat supply to each individual boiler when the amount of water in that generator is unduly low, or when the conditions of operation in any boiler are such as to create excessive foaming and the consequent carrying into the steam main or header of unduly large amounts of entrained water.

A further object of the invention is to provide improved means for maintaining efficient combustion conditions in each boiler furnace of the system, and in particular for maintaining a desirable CO_2 content in the flue gases formed in each boiler furnace.

The various features of novelty which characterize my invention are pointed out with particularity in the claims annexed to and forming a part of this specification. For

a better understanding of the invention, however, and the advantages possessed by it, reference should be had to the accompanying drawings and descriptive matter, in which I have illustrated and described a preferred embodiment of the invention.

Of the drawings:

Fig. 1 is a diagrammatic representation of a preferred embodiment of my invention;

Fig. 2 is a larger scale view of the master controller employed in Fig. 1;

Fig. 3 is a diagrammatic representation of a modified form of the compensating master controller shown in Fig. 2;

Fig. 4 is a diagram illustrating a control circuit modification; and

Fig. 5 is a diagram illustrating another modification.

In Fig. 1 of the drawings, I have illustrated the use of my invention in connection with a control system for regulating combustion conditions in a plurality of boilers A (only one of which is shown in Fig. 1) delivering steam to a common header or steam distribution piping system A'. The steam generator A shown in Fig. 1 comprises a so-called vertical water tube boiler having upper steam and water drums a connected by banks of water tubes a' to a lower water drum a², with the usual baffles a³ for directing the flow of the heating gases from the combustion chamber A' of the generator to the stack outlet A².

As shown, the boiler is heated by the combustion of solid fuel on a stoker grate b at a rate dependent upon the speed of the stoker motor B. The air to support combustion is supplied by a blower c, the outlet conduit C' of which leads directly to the primary air inlet A² through which air passes to the underside of the fuel bed, and which also supplies air through a branch conduit C² to a secondary air inlet A²⁰ opening directly to the combustion chamber A' above the fuel bed. Advantageously, the speed of the blower motor C is controlled by an automatic controller KC as hereinafter described, so as to minimize the power consumed by the motor C while insuring an adequate air supply at all times. The pressure in the combustion cham-

ber is directly controlled by a damper *d* located in the conduit *C'*. The division of the total amount of air supplied between the primary and secondary inlets *A*² and *A*²⁰ is regulated by a damper *e* in the conduit *C*². The volume of draft through the furnace is controlled, in the system shown in Fig. 1, by the adjustment of a stack damper or stack dampers *f*.

The intended operation of the particular embodiment of the control system illustrated in Fig. 1, results in the adjustment of the speed of the stoker motor *B* by a controller *KB* and the operation of the motor *MF* by a controller *KF* to adjust the stack dampers *f* as required to make the rate of fuel supply and the volume of draft, respectively, each normally proportional to the steam load, i. e., the rate at which steam is withdrawn from the header or main *A*⁷. The proportion may be varied from time to time, however, as a result of individual boiler water conditions, and in order to restore the header steam pressure to its predetermined value when, as a result of load changes and of time lag in the furnaces and in the operation of the control mechanism, the header steam pressure has departed from its normal value.

The controller *KB* acts through a reversible motor *MB* on a stoker controller *B*² as hereinafter explained to control the stoker speed, and the controller *KF* effects adjustments of the dampers *f* through its action on a reversible relay motor *MF*.

In the particular embodiment of the invention shown in Fig. 1, the damper *d* is adjusted as required to maintain a predetermined pressure in the combustion chamber *A'*, by a furnace pressure controller *KP* which is so associated with the control system as to make the absolute furnace pressure diminish and increase as the rate of combustion increases and diminishes. The controller *KP* acts on the damper *d* through a reversible relay motor *MD*. As shown in Fig. 1, also, the damper *e* is controlled by a CO_2 machine *H* in such manner as to maintain an approximately constant CO_2 flue gas content in the furnace chamber at the point *A*⁸ at which the sample gas connection *H'* from the CO_2 machine *H* opens to the combustion chamber, the controller *H* acting on the damper *e* through a reversible motor *ME*.

In the arrangement shown in Fig. 1, the desired relation between the steam load on the one hand, and the rate of fuel supply, the volume of draft, and the gas pressure in the furnace chamber *A'* of each generator *A* on the other hand, is maintained by subjecting the hereinbefore mentioned controllers *KB*, *KF* and *KP* pertaining to each generator *A*, to the action of a control force which is adjusted as hereinafter explained in response to changes in the header steam pressure as required to restore the header steam pressure to

the desired or normal value. In the arrangement shown in Fig. 1, this control force is an electric current flowing through a main control circuit individual to each generator *A*.

In Fig. 1, 3 represents the main control circuit for the generator *A* shown, and 3A, 3B and 3C represent portions of the control circuits for three other generators (not shown) which supply steam to the main or header *A*⁷. Each of these control circuits is connected to, and energized from, supply conductors 1 and 2 between which a constant potential difference is maintained. The strength of the current flowing through the control circuit 3 is normally and primarily controlled by a master controller *K* responsive to the header steam pressure. The controller *K* produces its control effect by varying the portion of a resistance *R'* in the control circuit. As shown, the strength of the current flowing through the control circuit 3 is also dependent on the adjustment of resistances *R*², *R*³ and *R*⁴ in that circuit. The resistance *R*² is intended to be manually controlled, but the resistances *R*³ and *R*⁴ are automatically adjusted in response to variations in water level and degree of foaming in the generator *A* as hereinafter explained. Resistances similar to the resistances *R'*, *R*², *R*³ and *R*⁴ are associated with each of the control circuits 3A, 3B and 3C. The master controller *K* exerts its controlling effects on the control circuits 3, 3A, 3B and 3C by effecting simultaneous adjustments in the resistances *R'* individual to those circuits.

In the arrangement shown in Fig. 1, the amount of each of the resistances *R'* included in the corresponding control 3, 3A, 3B and 3C at any one time, depends upon the then relative positions of a pivoted contact carrying arm *K*⁵, and a rheostat body *r* supporting the resistances *R'* and movable in a direction transverse to the length of the contact arm *K*⁵ and parallel to the plane of movement of that arm. As shown, the rheostat body *r* is guided in its movement by stationary guide-pins *r*² passing through slots *r*¹ in the resistance body. The resistance body is given its movement by a reversible relay motor *MR* diagrammatically shown as having a threaded spindle passing through a threaded opening in a lug *r*³ carried by the resistance body *r*. The arm *K*⁵ carries a contact shoe *K*⁵⁰ which engages the resistances *R'* and is connected, as shown, to the supply conductor 2.

The master controller *K* comprises a pressure chamber *K'* to which the header steam pressure is transmitted by a pipe connection *K*³, and the top wall of which is formed by a diaphragm *K*² acting on a lever *K*⁴. The movements of the latter are caused to give suitably proportioned movements to the lever *K*⁶ by connections shown as comprising a lever *K*⁷ fulcrumed at *K*⁸ and connected to

the lever K^4 by a link K^6 and connected to the lever K^5 which is fulcrumed at K^{65} by a link K^6 . The linkage shown is intended to amplify the movements of the lever K^5 as compared with the movements of the lever K^4 , and the degree of amplification may be varied by adjusting the connections between the link K^6 and the levers K^5 and K^7 longitudinally of those levers. The thrust of the diaphragm K^2 on the lever K^4 is opposed by a loading spring K^{41} and by a weight K^{40} carried by the lever. The weight K^{40} may be adjusted along the length of the lever to thereby vary the normal header steam pressure which the control system tends to maintain; namely, that at which the arm K^5 is in the normal horizontal position shown and the contact member K^{51} carried by the arm K^5 is out of engagement with stationary contact conductors Q' and Q^2 .

As diagrammatically shown, the motor MR is provided with two windings which have one common terminal connected to one terminal of a source of current MR' . The opposite terminal of said current source MR' is connected to the contact shoe K^{51} carried by the pivoted arm K^5 . The second terminal of one of the two windings of the motor MR is connected to the contact conductor Q' , and the second terminal of the other winding is connected to the contact conductor Q^2 . When the arm K^5 moves out of a normal intermediate position in the counter-clockwise direction, the shoe K^{51} engages the contact conductor Q' and thereby energizes one winding of the motor MR which then begins to rotate in one direction. Conversely, when the arm K^5 moves away from its normal intermediate position in the clockwise direction the contact shoe K^{51} engages the contact conductor Q^2 and thereby energizes the second winding of the motor MR which then begins to rotate in a direction opposite to that in which the motor rotates when the contact K^{51} engages the contact conductor Q' .

If, as indicated in the drawings, the contact conductors Q' and Q^2 are so arranged that the resistance in whichever of the corresponding motor winding circuits is energized diminishes as the extent of displacement of the arm K^5 away from its neutral position increases, the speed of the motor MR will be greater or less according to the extent of said displacement. Advantageously, each winding of the motor MR includes a resistance R^{10} which may be adjusted to vary the speed of the motor MR for any given displacement of the arm K^5 .

When, as a result of an increase in the header pressure, the lever K^5 is tilted in the counter-clockwise direction, the initial effect is to increase the resistance R' in each control circuit, and to bring the contact shoe K^{51} carried by the lever K^5 into engagement with the contact conductor Q' . When the shoe

K^{51} engages the conductor Q' the motor MR is energized from a current source MR' to rotate in the direction to lower the rheostat body r . This further increases or tends to increase the amount of each resistance R' in the corresponding control circuits 3, 3A, 3B and 3C, and thereby decreases the strength of the control current in each of the main control circuits, and correspondingly reduces the volume of draft in, and the rate of fuel supply to the corresponding steam generators A . Conversely, on a reduction of the steam pressure in the header A' below the normal value the lever K^5 tilts in the clockwise direction decreasing the amount of each resistance R' in the control circuit and bringing the shoe K^{51} into engagement with the contact conductor Q^2 , whereupon the motor MR is energized from the source MR' to run in the direction required to raise the rheostat body r and further decrease the amount of each resistance R' then included in the corresponding control circuit, so as to increase the rate of combustion in each boiler furnace.

It will be readily apparent that the lever K^5 will occupy its normal intermediate position in which it does not engage either the contact Q' or the contact Q^2 only when the steam pressure in the header A' is at the normal value determined by the adjustments of the weight K^{40} , and that the lever K^5 can remain in this normal position only when the rate of combustion in the various steam generators in service is such as to insure a rate of steam generation without change in boiler steam pressure, which is equal to the demand for steam. Any variation in the ratio between heat supplied to the boilers supplying steam and the demand for steam results in a change in header steam pressure which sets the master controller into operation to restore the ratio.

The various controllers KB , KF and KP through which variations in the control force modify the rate of fuel feed, the volume of draft and the combustion chamber pressure, respectively, in each boiler furnace, may be of any usual and suitable form. Various instrumentalities suitable for the purpose are well known. As diagrammatically illustrated in Fig. 1, the controllers KB , KF and KP are of types heretofore developed by me and illustrated in prior patents granted to me.

The stoker controller KB as shown includes a pressure chamber P , one wall of which is formed by a diaphragm P' exposed at its outer side to the pressure of the atmosphere. Associated with the pressure chamber P are means for maintaining in that chamber a pressure which is less than that of the atmosphere by an amount proportional to the square of the stoker speed. As shown, those means comprise a tachometer fan or blower B' which is driven by the stoker motor at a

speed proportional to the speed of the latter, and which has its outlet open to the atmosphere and has its inlet connected by a pipe P^2 to the pressure chamber P . The diaphragm P' acts on a lever K^{10} fulcrumed at K^{11} . The lever K^{10} carries at one end the floating coil K^{12} of an electro-dynamometer of the Kelvin balance type comprising stationary coils K^{13} located at opposite sides of the coil K^{12} . The coils K^{12} and K^{13} are connected in series in the control circuit 3 and interact to exert a torque on the lever K^{10} which is proportional to the square of the control current flowing through the circuit 3 and which opposes the differential pressure effect on the diaphragm P' of the atmosphere and the tachometer fan suction.

In consequence of the arrangement described, the lever K^{10} of the balance KB will 20 occupy a normal intermediate position only when the speed of the stoker is in predetermined proportion to the strength of the current flowing in the control circuit 3. On an increase or decrease in strength of the control current relative to the stoker speed, the resultant clockwise or counter-clockwise movement of the lever K^{10} effects a corresponding adjustment of the stoker speed controller B^2 serving to respectively increase or 30 decrease the stoker speed and thus restore the balance. As diagrammatically illustrated, the adjustment of the speed controller B^2 is effected by means of a reversible relay motor MB . The motor MB may be exactly like 35 the motor MR and be controlled in the same way as the latter. As shown, however, the controlling provisions for the motor MB are not intended to provide such a graduated speed control of that motor as is obtained 40 with the motor MR , and in lieu of the specially arranged contact conductors Q' and Q^2 associated with the motor MR , a simple contact arrangement comprising contacts Q^{10} and Q^{20} , is employed to close one or the other 45 of the two energizing circuits of the motor MB when the lever K^{10} of the controller KB tilts in the counter-clockwise or clockwise directions, respectively.

As shown, the stack damper controller KF 50 is in substance exactly like the stoker controller KB , the damper operating motor MF being controlled by the balance lever K^{10} of the controller KF . As shown, the lever of the controller KF is pivotally supported by a 55 flexible suspension K^{100} , while the lever of the controller KB has a knife-edge fulcrum bearing. The pressure chamber P of the controller KF is connected by pipe P^2 to the stack gas outlet A^3 of the boiler A at the 60 inlet side of the stack dampers f . In consequence, the controller KF adjusts the dampers f as required to maintain a pressure at the stack gas outlet of the boiler which is less than that of the atmosphere by an amount 65 proportional to the strength of the

control current in the circuit 3. This serves, as hereinafter explained, to maintain a volume of draft through the furnace A which is proportional to the strength of the control current in the circuit 3. 70

The furnace pressure controller KP , as shown, is also similar in construction and arrangement with the controllers KB and KF . The pressure chamber P of the controller KP is connected by a pipe P^2 to the 75 combustion chamber A' of the steam generator A . The motor MD is controlled by the lever K^{10} of the balance KP exactly as the motors MB and MF are controlled by the levers K^{10} of the balances KB and KF , respectively. The controller KP thus serves 80 to adjust the damper d as required to maintain a combustion chamber pressure less than that of the atmosphere by an amount proportional to the square of the control current 85 flowing in the circuit 3. 90

With the minus pressures (pressures less than that of the atmosphere) maintained in the combustion chamber and at the stack gas outlet of the generator A thus maintained by the respective controllers KP and KF , each proportional to the square of the control current, the difference between those pressures will also be proportional to the square of the control current. The volume of draft is proportional to the square root of the draft loss between the combustion chamber and the stack outlet since the intervening portion of the boiler serves in effect as a fixed orifice. Hence, the volume of draft is maintained proportional to the control current in the control circuit 3. Furthermore, if the furnace pressure controller KP is replaced, as it may be in some cases, by a so-called balanced draft controller serving to maintain 100 the combustion chamber pressure equal to that of the atmosphere, the difference between the combustion chamber pressure and the pressure in the furnace gas stack outlet A^3 which measures the volume of draft will 105 still be proportional to the strength of the control current passing through the coils of the controller KF , as will be readily apparent 110 to those skilled in the art. 115

Those skilled in the art will understand, of course, that the desired proportion maintained between the square of the control current and the pressure in the pressure chamber P of each of the balances KB , KF and KP , must be fixed at a suitable value dependent on the conditions of use and may require adjustment from time to time as conditions change. For example, if as a result of a change in the character of the fuel used it is desired to maintain a different fuel-air ratio at one time 120 from that maintained at another time, some adjustment in either or both of the balances KB and KF should be made. One simple method of effecting such an adjustment is to provide an adjustable resistance shunt R^{20} 125

about the coils K^{12} and K^{13} of each of the different balances KB, KF and KP. The resistance shunt R^{20} about the coils of the balance KF would require adjustment, for example, to compensate for such a change in operating conditions as would be involved in the replacement of the balance KP by a controller maintaining a constant pressure in the combustion chamber, while the shunt R^{20} about the coils of the balance KB may be adjusted to compensate for a change from a fuel of one heating value to a fuel of a different heating value.

The apparatus shown in Fig. 1 includes a feed water regulator S diagrammatically shown as comprising a float chamber extending above and below the normal boiler water level and connected by pipes S' and S^2 to the front steam and water drum a of the boiler at points above and below the water level therein. This chamber may form an extension of, or constitute a portion of, the steam and water space of the boiler, though preferably it is separated from the latter to protect the float S^3 therein against some of the surges and ebullition effects occurring in the main steam and water drum. The float S^3 is pivotally supported at S^4 and is connected to a valve member S^5 which is moved by the float S^3 as the water level rises and falls through its normal range to more or less completely close the feed water inlet S^6 . The float S^3 and valve S^5 thus limit the maximum height of water level in the boiler regardless of the tendency of the boiler feed system to continue the supply of water at that time.

The boiler feed system shown in Fig. 1 includes a feed water boiler pump T which delivers water to the feed water inlet S of the boiler A through the feed pipe T'. There may be an individual boiler feed pump T for each boiler, or all of the boilers may be supplied by a single feed pump. The boiler feed system contemplated in the particular arrangement is one tending to maintain a delivery pressure in each pipe T' which is in excess of the boiler steam pressure when the inlet S⁶ is throttled. The full excess pressure thus created may be of a constant value, or it may increase and decrease with the boiler load. Various boiler systems of each of the kinds referred to are known and may be used.

If, as will be the case with the preferred form of feed regulation contemplated, the pressure in the feed pipe T' builds up somewhat above the boiler pressure as the valve S⁵ prevents or throttles the discharge of water into the boiler, I advantageously employ this pressure building up to exert a desirable modification in the control current flowing through the control circuit 3. To this end, I show in Fig. 1 a differential pressure device t divided into two chambers t' and t^2 by a diaphragm t^3 . The chamber t' is connected to the feed pipe T', and the chamber

t^2 is connected to the steam and water space of the boiler by the pipe t^4 . The diaphragm t^3 is connected to a rock shaft t^5 so that the movement of the diaphragm resulting from a pressure in the chamber t' higher than the pressure in the chamber t^2 will oscillate the shaft t^5 in the counter-clockwise direction. The shaft t^5 carries a contact arm t^6 engaging the previously mentioned resistance R^3 in the control circuit 3. When the shaft t^5 is turned in the counter-clockwise direction the amount of resistance R^3 in the control circuit 3 is reduced, and when the shaft t^5 is turned in the other direction the amount of resistance in the control circuit 3 is increased, and preferably the arm t^6 separates from the resistance R^3 and opens the control circuit 3, when the water level falls below a predetermined normal safe minimum.

In the contemplated mode of operation of the apparatus shown, the boiler water level will be maintained at such height as to normally cause the valve S⁵ to partially throttle the feed inlet S⁶. Preferably, none or only a relatively small portion of the resistance R^3 is then included in the control circuit 3. On a decrease in the boiler water level the amount of resistance R^3 included in the circuit is increased. Security against the possibility of supplying heat to a boiler at a high rate when the water level is dangerously low or when the feed supply pressure fails, is insured by arranging the arm t^6 and the resistance R^3 so that when the feed inlet is subject to no throttling effect whatever by the valve S⁵, the arm t^6 will move into a position in which it separates from the resistance R^3 and thus opens the control circuit 3.

Advantageously, in some cases, I provide means for diminishing the rate of combustion in any of the controlled boilers when as a result of excessive load or other causes an unduly large amount of water is being carried out of the boiler through its steam delivery pipe A⁴. These provisions, as shown in Fig. 1, comprise a steam and water separating chamber U interposed between the steam pipe A⁴ and the superheater A⁵ through which the steam is passed and from which it is delivered through the pipe A⁶ to the header A⁷. The separator chamber U is provided with an outlet U' to a steam trap or other means for discharging collected water which is so restricted that when the rate at which entrained water collects in the chamber U is relatively large, the water level therein builds up and thereby raises a pivoted float U². The raising of the float U² rotates a supporting shaft U³ carrying an external rheostat arm U⁴ engaging the resistance R⁴ and forming a part of the control circuit 3. The effect of raising the float U² is to increase the resistance R⁴ in the control circuit and thereby

diminish the rate of combustion in the particular boiler.

The control circuit resistances R^3 and R^4 adjusted as previously described, are of especial utility in a steam generating plant comprising a plurality of boilers controlled in the general manner described, for the reason that they tend to so divide the load among the different boilers as to decrease the portion of the load carried by a boiler or boilers in which operating conditions are relatively unfavorable while at the same time correspondingly increasing the portions of the load carried by the boilers in which operating conditions are better.

The CO_2 machine H controlling damper e may be of any usual or suitable form. One form suitable for the purpose is shown in my prior Patent No. 1,564,553, granted December 8, 1925, and other suitable forms are known. As shown, the machine H comprises a circuit controller H^2 deflected in one way when the CO_2 content of the gases passing to the machine through the pipe H' exceeds a predetermined value, and deflected in the opposite direction when the CO_2 content is below a predetermined value. The contact H^2 when deflected from its neutral position, closes one or the other of two energizing circuits for the reversible motor ME employed to adjust the damper e . The motor ME with its circuits may be like the motors MB , MF and MD and their circuits.

As previously explained, the forced draft fan motor C is advantageously so controlled as to insure an adequate supply of air at all times while minimizing the power consumption of the motor. In the form of my invention shown in Fig. 1, the power consumption of the motor is minimized by the controller KC , which increases and decreases the speed of the motor C as the need for air increases and decreases. The controller KC comprises means responsive to the pressure differential at the opposite sides of the damper d and serves to speed up the fan c when the differential falls to a predetermined minimum value, and to diminish the speed of the fan when this differential rises to a predetermined maximum.

The controller KC is shown as including a differential pressure device comprising two pressure chambers C^3 and C^4 connected to the draft duct A^2 at the delivery and inlet sides, respectively, of the damper d . One wall of each of the pressure chambers C^3 and C^4 is formed by a diaphragm, and the outward thrust of each diaphragm opposes that of the other through the engagement of the diaphragms with a lever C^5 having a fulcrum bearing at C^6 . The lever and diaphragms are so arranged that the lever will assume a neutral position only when the pressure in the chamber C^3 exceeds that in the chamber C^4 by a predetermined amount, which may

be varied by shifting the fulcrum C^6 and/or the adjustment of a weight C^{50} carried by the balance.

When the lever C^5 is turned in the counter-clockwise direction in consequence of a decrease in the difference between the pressure transmitted to the chambers C^3 and C^4 , it engages a contact C^7 and thereby closes a control circuit comprising the contact C^7 , a conductor 5, a solenoid winding C^9 , a conductor 7, a source of current 8, an interrupter C^{11} normally engaging a contact 9, and the lever C^5 to which the contact 9 is connected through the lever fulcrum C^6 . Conversely, when the differential between the pressures transmitted to the chambers C^3 and C^4 exceeds a predetermined amount, the lever C^5 is deflected in the clockwise direction and closes a control circuit including the contact C^8 , conductor 6, solenoid winding C^{10} , conductor 7, current source 8, interrupter C^{11} , contact 9, and lever C^5 .

The interrupter C^{11} may advantageously be of the bimetallic thermostatic type, arranged to be heated in a brief period by the control current flowing, whenever the lever C^5 engages either contact C^7 or C^8 , and which when so heated, deflects and separates from the contact 9. After cooling off for a brief period the thermostatic interrupter C^{11} deflects back into engagement with the contact 9. The thermostatic interrupter C^{11} thus serves to alternately open and close the control circuit at suitable intervals of a few seconds or a minute, or so, during any period of operation in which the lever C^5 is in engagement with either contact C^7 or C^8 .

The solenoid coils C^9 and C^{10} in the arrangement shown, are co-axial and spaced apart, and serve when either is energized to attract a solenoid core C^{12} carried by a rod C^{120} co-axial with the coils and lengthwise movable in the direction of its length in guides C^{18} . The core C^{12} is normally held in a position intermediate of the coils C^9 and C^{10} by springs C^{15} acting on a projection C^{14} from the rod C^{120} . The movement of the core C^{12} in either direction from its intermediate position serves to give a corresponding adjustment to a brush C^{24} engaging a speed regulating resistance R^{10} which with the brush C^{24} is included in a speed controlling circuit of the motor C .

The particular mechanism shown through which the core C^{12} thus adjusts the amount of speed controlling resistance R^{10} included in the motor circuit, comprises a double pawl member C^{16} pivoted to the core carrying rod C^{120} at C^{17} , and having two oppositely extending pawls C^{18} and C^{19} . The pawl member C^{16} is formed with an oppositely inclined cam surface C^{20} which engages a stationary pin C^{25} and thereby causes the member C^{16} to tilt in one direction or the other when the rod C^{120} is moved in one direction or the

- other from its intermediate position. The cam surface C^{20} is so shaped that when the core C^{12} is moved toward the coil C^9 by the energization of the latter, the pawl member C^{18} is tilted by the pin C^{25} into the position in which the pawl C^{19} engages one of the teeth C^{22} of a rack bar support C^{23} for the brush C^{24} and thereby causes the bar C^{23} and brush C^{24} to move with the core during a portion of the movement of the latter. When the core C^9 is de-energized and returns to its intermediate position the pawl member C^{16} is returned to its normal intermediate position without effecting any retrograde movement of the bar C^{23} . Successive energizations of the coil C^9 gives additional movements in the same direction as before to the rack bar C^{23} . Whenever the coil C^{10} is energized, however, the resultant movement of the core C^{12} causes the pawl C^{18} of the pawl member C^{16} to engage a tooth C^{22} of the rack bar C^{23} and moves the brush C^{24} in a direction opposite to that in which it is moved by the energization of the coil C^9 .
- As shown, the portion of the resistance R^{10} in the motor circuit is increased or decreased by the controller KC when the pressure drop past the damper d in the duct A' falls below or exceeds predetermined limits and thus serves to increase or decrease the speed of the motor C . To this end the resistance R^{10} may well be included in the field circuit of the motor C . The operation of the controller KC is thus to effect a step by step adjustment of the speed of the blower fan motor C as required to insure an output of the fan c at all times ample for the control effected by the damper d and its controller KP , without the waste of power which would be involved if the fan c were operated at all times at the speed necessary to furnish the air required under maximum load conditions, while at the same time the control of the motor C is not of the character tending to make the speed of the motor fluctuate or hunt. The described step by step adjustment mechanism insures a full stroke at each operation, and avoids the possibility of having the motor controller stop between rheostat points.
- In the practical use of a control system of the type described, any quickly effected change of appreciable magnitude in the header steam pressure will normally occur only as the result of a significant change in the steam load or rate at which steam is withdrawn from the boiler or boilers in service through the header A' . Since the rate at which heat is withdrawn from the boilers is approximately proportional, under all practical conditions of operation, to the rate at which steam is withdrawn, it is, in general, desirable, that any change in header steam pressure should result in a change in the rate of combustion approximately proportional to the change in steam load producing the

change in header pressure. In other words, on a change in header steam pressure it is in general desirable that the strength of the control current flowing in each of the circuits 3, 3A, 3B and 3C should be varied in definite relation to the change in the steam flow rate through the header A' which produced the change in header steam pressure.

When all of the boilers supplying steam to the header A' are subject to the automatic control system and have their rates of combustion varied simultaneously and proportionally, the control currents flowing in the circuits 3, 3A etc. should normally vary in linear proportion to the header steam flow rate as the latter changes with the demand for steam. In such case, the change in the header steam pressure occurring on an increase in the rate at which steam is withdrawn will be expressed by the equation:

$$(P_0 - P_1) = A(L + d)^2$$

wherein A is a constant, P_0 equals the standard or normal header pressure, and P_1 is equal to the new value of the header steam pressure produced after a given steam load has been increased by an amount d . The quantities L and d may be expressed in pounds or cubic foot of steam flowing per unit of time or in units of linear velocity of steam flow through the header A' . On a load decrease (d) the same equation applies, but in such case it is to be noted that d and $(P_0 - P_1)$ are each negative.

From the equation given above, it will be apparent that a given change, $\pm(P_0 - P_1)$, in header steam pressure corresponds to a greater steam load difference, $\pm(d)$, when the previous steam load (L) is small than when the latter is larger. In general, therefore, the change in the amount of resistance R' in any control circuit 3, 3A, etc. produced by a given change in the header steam pressure should be smaller when the steam load is relatively large than when the steam load is relatively small. This result may be secured by arranging the resistance conductors R' as indicated, so that the resistance per unit of length measured parallel to the general direction of the resistance progressively increases from the bottom to the top of the resistance.

Those skilled in the art will understand that with all of the boilers supplying steam to the main A' , subject to the control system shown in Fig. 1, the control force in each control circuit will vary with the load if the corresponding resistance R' is so proportioned that the total resistance in the control circuit varies in inverse proportion with the steam flow through the header.

If with the arrangement shown in Fig. 1, all, or substantially all, of the drop in steam pressure between each boiler and the point in the header at which the pipe K^3 is con-

nected, occurs in the piping, including the superheater, between the boiler proper and the header, the control system does not have to be recalibrated or subjected to any significant adjustment when the number of boilers in service is increased or diminished. In such case, when a boiler is cut into or out of service, all that is required, so far as the control system is concerned, is the closing or opening of the corresponding switch 30. Except for the purpose of providing for the operation of more boilers at one time than at another, it is not necessary with the regulation apparatus shown in Fig. 1, to employ more than a single resistance R' . With a single resistance R' , the various controllers KB, KF and KP for the different boilers may have their coils K^{12} and K^{13} connected in series with one another, and with the resistance R' , or the coils of the different controllers for each boiler may be connected in an individual circuit portion 300, 300A, 300B or 300C as shown in Fig. 4, these individual circuits being in parallel with one another and each in series with the single resistance R' .

Those skilled in the art will understand that the ideal condition obtainable with the control system shown in Fig. 1, when all of the boilers are subjected to the control system so that each boiler carries a constant portion of the total load at all times, is not always obtainable, and for other reasons is not always desirable in practice. For example, it is frequently desirable in some plants to maintain approximately constant rates of combustion in some of the boilers, then commonly referred to as "steady load" boilers, while taking care of the fluctuations in the total steam load with other boilers commonly referred to as "variable load" boilers. In such case, the variable load boilers only are subject to the control system of Fig. 1.

With the control system shown in Fig. 1, if one or more of the boilers delivering steam to the main A⁷ are subject to the control system, and one or more other boilers are operated as "steady load" boilers, the ultimate effect of the control system on the boilers subject to its control is that desired, but the immediate control effect on the controlled boilers in response to a sudden and appreciable change in load cannot be in the same proportion to the load change, under all conditions at least, if the steady load boilers have appreciable heat storage capacity. A change in header pressure occurring on a change in load requires a change in the boiler steam pressure of each of the steady load boilers. When, as is the case with all ordinary boilers, the steady load boilers have significant heat storage capacity, some time is required for the change in boiler steam pressure of the steady load boilers, which results from a change in the header pressure.

During the period in which their pressures are changing, the steady load boilers will deliver steam at a rate which is higher or lower than the normal rate, accordingly as the header steam pressure change resulting from the load change is a decrease or increase.

In installations in which all, or the major portion of, the steam pressure drop is in the header, as distinguished from the pipe connections between the header and the individual boilers, it is in general desirable that the boilers subject to the control system have the coils of their balances KB, KF and KP connected in series with a single resistance R' , for example, as in the arrangement shown in Fig. 4. With such a series arrangement, when a boiler is put under steady load operation, it is desirable to substitute for the windings K^{12} and K^{13} of the controllers pertaining to the boiler cut out, and for any portion of the control circuit peculiar to that boiler, an equivalent resistance R^{20} , as shown in Fig. 4. In such case, as with the modification of the system shown in Fig. 1 involving the operation of steady load boilers described above, the immediate response of the master controller cannot effect the ideally required adjustment of the resistances R' under all conditions of operation. In all of the cases referred to, however, better results are obtainable by an arrangement of the resistance or resistances R' employed, such as is illustrated in the drawings hereof, which serves to make the change in the portion of each resistance R' in use, greater when the steam load changed is relatively small than when the steam load changed is relatively large.

In Fig. 5 I have illustrated another form of the invention especially adapted for use in a plant comprising a battery of boilers, and in which all, or the major portion of the significant steam pressure drop between the boilers and the point in the main at which the master controller is connected, is due to resistance in the main rather than in the individual connections to the main from the boilers, as might be the case, for example, if all the boilers pass steam to the main through a common independently fired superheater. With the arrangement shown in Fig. 5, one or more of the boilers may be operating under steady load conditions, one or more others may be operating under variable load conditions, and one or more may be out of service at any one time, and at all times the control apparatus tends to make the rate of combustion in the boilers operating under variable load that required to enable them to carry their loads.

In the arrangement shown in Fig. 5 the master controller KB might be identical with that shown in Fig. 1, but as shown differs therefrom in that the main lever K⁴ of the controller KB carries the resistance engaging

members K^{50} and K^{51} which are carried by the lever K^5 in Fig. 1. The controller KB operates to maintain a current flow in a circuit 301 which is a function of the pressure in the steam main A^7 receiving steam from so many of the boilers of the plant as are in service. The circuit 301 includes a single regulating resistance R' carried by the resistance body r , and also includes the coil X' of a current balance X of known type shown, for example, in my prior Patent No. 1,166,758.

The balance X comprises a second coil X^2 , and a lever X^3 so fulcrumed that the electromagnetic interactions between the two coils and their movable cores X^4 and X^5 , respectively, which are pivotally suspended from the lever, oppose one another. The coil X^2 has one terminal connected by a conductor 10 to the current supply main 1 and has its other terminal connected by a conductor 11 to a steady load bus bar 12, and by a conductor 13 to a variable load bus bar 14. Included in series with the conductor 13 is a rheostat comprising a resistance R^{13} and a rheostat arm Z adjusted by a reversible relay motor MX .

When the current flow through the coil X^2 exerts a pull on the magnet core X^5 which exactly balances the opposing action on the lever X^3 of the pull due to the current flow in the coil X' on the core X^4 , the lever X^3 assumes a neutral position and the motor MX is then de-energized. When, as on an increase in load, the current flow through the coil X' increases relatively to the current flow through the coil X^2 , the lever X^3 tilts and closes contacts Y' thereby energizing one of the circuits of the motor MX . The latter then rotates the rheostat arm Z in a counter-clockwise direction and thus reduces the amount of resistance R^{13} in circuit with the conductor 13, until the current flow through the coil X^2 is increased as required to restore the balance and return the lever X^3 to its neutral position. On a decrease in load and resultant decrease in the current flow through the coil X' , the lever X^3 tilts to close the contacts Y^2 and thus energize the motor MX in the direction required to turn the rheostat arm Z in the clockwise direction and thereby increases the portion of the resistance R^{13} in circuit with the conductor 13 until the resultant decrease in current flow through the coil X^2 restores the balance lever X^3 to its neutral position.

In Fig. 5 A_1 , A_2 , A_3 and A_4 represent the control mechanisms for corresponding boilers. One terminal of each control mechanism is connected to a bus bar 15 connected in turn to the supply conductor 2 by a conductor 16. The other terminal of the control mechanism for each boiler is connected through a manually adjustable resistance R^2 to a switch blade 31. The latter may be adjusted into one position in which it is con-

nected to the variable load bus bar 14, into a second position in which it is connected to the steady load bus bar 13, or into an off position in which it is not connected to either bus bar, the latter position being occupied when the corresponding boiler is out of service. As shown, the boiler to which the control mechanism A_1 pertains is operating under steady load, the boiler to which the mechanism A_2 pertains is out of service, and the boilers to which the mechanisms A_3 and A_4 pertain are operating under variable load.

In operation, the master controller KB of Fig. 5 maintains a current flow through the coil X' which is proportional to the load. The balance X operates through the motor MX to maintain a current flow in the coil X^2 which is proportional to the current flow through the coil X' , and hence is also proportional to the load. The boiler control mechanism or mechanisms, (A_1 as illustrated), for the boiler or boilers operating under steady load take whatever portion of the current flow through the coil X^2 corresponds to the load to be carried by the boiler, or boilers, operating under steady load and having their control mechanisms connected to the steady load bus bar 12. The remainder of the current flow through the coil X^2 passes to the variable load bus bar 14 and thence through the control mechanism or mechanisms of the boiler or boilers operating under variable load. With this arrangement a boiler may be cut into or out of service, or transferred from operation under steady load to operation under variable load, without requiring any change of the control apparatus other than the adjustment of the corresponding switch 31, and at all times the control system tends to maintain a rate of combustion in each boiler connected to either bus bar 12 or 14, which is that required to enable the boiler to carry its proper load.

The master controller employed may depart widely from the form illustrated diagrammatically in Figs. 1 and 2 without impairment of its capacity for performing some or all of the regulating functions previously described. For example, the master controller in some cases may advantageously be of the type illustrated in Fig. 3. The master controller KA , shown in Fig. 3, differs from the controller K principally in the manner in which the motor MR shifting the rheostat body is controlled, and in the fact that the pressure responsive device of the controller KA does not directly engage and adjust the resistance R' .

In the master controller KA , a contact arm K^{52} , which is movable independently of the controller arm K^4 , performs the control circuit resistance engaging function performed in the controller K by the contact K^{50} engaging the resistances R' , which in this form are stationary. The arm K^{52} is carried by a

frame K^{53} which is mounted and adjusted by the motor MR as is the rheostat body r of the controller K . In the master controller KA the energization of the motor MR is directly controlled by the engagement of a contact K^{54} carried by the lever K^4 with the contact conductors Q' and Q^2 . The contacts Q^1 and Q^2 of the controller KA are carried by a member r^{10} which is mounted on the frame K^{53} to move relative to the latter in a direction parallel to the direction of movement imparted to the frame by the motor MR . This relative adjustment of the parts K^{53} and r^{10} is effected by a motor mr mounted on the frame K^{53} and shown as having a threaded spindle passing through a threaded opening in the member r^{10} . The energization of the motor mr is controlled by the engagement of a contact K^{55} carried by the lever K^4 of the balance KA with one or the other of elongated contacts Q^{101} or Q^{201} .

On a decrease in the header stream pressure and the consequent clockwise deflection of the lever K^4 of the master controller KA , the motor MR is energized to move the frame K^{53} in the direction to diminish the amounts of the resistances R' included in the various control circuits 3, 3A, 3B and 3C. At the same time, the motor mr is energized in the direction to move the member r^{10} relative to the frame K^{53} in a direction opposite to the absolute movement of the latter. The adjustments thus initiated continue until the header pressure is restored to its normal value at which time both of the motors MR and mr will be de-energized. Conversely, upon an increase in the header steam pressure the motors MR and mr are actuated in the opposite directions and the amounts of resistances R' in the various control circuits are thereby increased until the header pressure is restored to its normal value and the lever K^4 is returned to its normal neutral position.

Since with the form of the master controller KA shown in Fig. 3, the pressure responsive device is not employed to directly adjust the resistances R' , that device may be made lighter and more sensitive than is necessary with the form of controller shown in Fig. 1 and Fig. 2. With the form of master controller shown in Fig. 3, the motor MR may be arranged to rapidly effect wide adjustments when required in the portions of the resistances R' included in the control circuit without any appreciable tendency of the control system to hunt, provided that the motor mr is made sufficiently slow acting to prevent its action from approaching too close synchronism with the responses of the controlled boilers to the changes in the rates of combustion produced by the adjustment in the resistances R' .

While in accordance with the provisions of the statutes, I have illustrated and de-

scribed the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. The combination with steam generating apparatus and piping receiving steam generated thereby, of a combustion control system including a master controller including an element moving in response to changes in steam pressure at a point in said piping at which the steam pressure varies in response to changes in steam load and in response to changes in boiler steam pressure, means for establishing an electrical combustion controlling force including a rheostat element cooperating with the first mentioned element to vary said force as the first mentioned pressure changes, by amounts which are greater or less, accordingly as the steam load prior to said change was relatively light or relatively heavy.

2. The combination with steam generating means and piping receiving the steam generated, of a combustion control system regulating the supply of heat to said means, comprising means for maintaining a regulable electrical control force including a rheostat and a master controller, the latter including a member moving in response to changes in steam pressure in said piping at a point at which the steam pressure changes in response to changes in the rate of steam delivery as well as in response to changes in the pressure at which the steam is generated, means controlled by the movement of said member away from a neutral position in either direction to effect an initial adjustment of said rheostat, and means set in operation by the movement of said movable member effecting a subsequent further adjustment of said rheostat at a rate increasing with the magnitude of the departure of said steam pressure from a predetermined value.

3. The combination with steam generating means and piping receiving the steam generated, of a combustion control system regulating the supply of heat to said means comprising means for maintaining a regulable electrical control force including a rheostat and a master controller, the latter including a member moving in response to changes in steam pressure in said piping at a point at which the steam pressure changes in response to changes in the rate of steam delivery as well as in response to changes in the pressure at which the steam is generated,

means controlled by the movement of said member away from a neutral position in either direction to effect an initial adjustment of said rheostat, and means set in operation by the movement of said movable member for effecting a subsequent further adjustment of said rheostat, said rheostat including provisions whereby the effect on the control force of a given change in the pressure impressed on the master controller is greater when the previous steam load has been relatively light than when it has been relatively heavy.

4. The combination with a steam generator and its steam outlet, of mechanism for regulating the supply of heat to the generator including means tending primarily to vary the supply of heat in proportion to the steam outflow through said outlet, and means responsive to the amount of water passing with the steam out of the generator through said outlet for adjusting said mechanism to diminish the ratio of heat supplied to the steam outflow as the amount of water carried out of the boiler increases.

5. The combination with a steam generator and its steam outlet, of combustion control provisions therefor including a control circuit and means tending to maintain a current flow in said circuit increasing and decreasing as the steam output increases and decreases, and means automatically responsive to the amount of water carried out of the boiler through said outlet for decreasing the current flowing in said control circuit as said amount increases.

6. The combination with a steam generator and its steam outlet, of combustion control provisions therefor including a control circuit and means tending to maintain a current flow in said circuit increasing and decreasing as the steam output increases and decreases, and means automatically responsive to the amount of water carried out of the boiler through said outlet for decreasing and increasing the current flowing in said control circuit as said amount increases and decreases.

7. The combination with a battery of boilers and a combustion control system responsive to the steam load carried by said boilers for regulating the combustion in the different boilers, of means associated with the individual boilers and responsive to the amount of water carried out of the different boilers with the steam delivered thereby for so modifying the action of said control system as to diminish the rate of combustion in each such boiler in which the amount of water discharged with the steam exceeds a predetermined height.

8. The combination with a steam generator, of means including a feed pipe for supplying feed water to said generator, means responsive to the height of water level in the generator for throttling said feed pipe

when the water level rises to a predetermined level, and pressure responsive means associated with said pipe for regulating the rate at which heat is supplied to said generator in accordance with the degree of throttling of said pipe.

9. The combination with a battery of boilers and a combustion control system responsive to the steam load carried by said boilers for regulating combustion in the different boilers of the battery, of means responsive to the height of the water level in individual boilers for so modifying the action of said control system as to diminish the rate of combustion in each such boiler when the water level therein diminishes below a predetermined height.

10. The combination with a steam generator and an automatic control system for regulating the rate of combustion therein and tending to maintain said rate proportional to the steam output of the generator, of means responsive to the height of water level in said generator for adjusting said system to diminish the combustion rate when said height of water level falls to a predetermined minimum value.

11. The combination with a furnace having separate primary and secondary air inlets, of means for supplying air under pressure in regulated aggregate amounts to said inlets, and means responsive to the CO_2 content of the gases of combustion for variably throttling the supply of air to the secondary air inlet so as to maintain said CO_2 content approximately constant.

12. The combination with a furnace having separate primary and secondary air inlets, of means for supplying air in regulated aggregate amounts to said inlets, and means responsive to the CO_2 content of the gases of combustion for variably throttling the supply of air to the secondary air inlet so as to maintain said CO_2 content approximately constant.

13. In a combustion control system, the combination with a draft creating motor, a speed controller for said motor, a draft regulating damper, and means responsive to the draft pressure drop past said damper for effecting one or more definite step adjustments of said controller when said pressure differential approaches either of predetermined desirable minimum and major values.

14. The combination with a steam generator having water storage capacity and a normal water level and an automatic control system for regulating the rate of combustion therein, of means responsive to the excess of the pressure at which the feed water is supplied to said generator over the steam pressure, for diminishing the combustion rate when said excess falls below a predetermined minimum.

15. The combination with a battery of

steam generating boilers and piping receiving steam generated thereby, of a combustion control system including a master controller including an element responsive to changes
5 in steam pressure at a point in said piping at which the steam pressure varies in response to changes in the steam load and in response to changes in boiler steam pressure, means for establishing an electrical battery
10 combustion controlling force, said means including a rheostat element, cooperating with the first-mentioned element to vary said force as the first-mentioned pressure changes, means for maintaining boiler electrical combustion controlling forces corresponding to the rates of combustion in the several boilers of the battery, and means for automatically adjusting one or more of the last mentioned forces while holding the other or others at a
20 constant value as required to maintain the aggregate value of said boiler forces proportional to said battery force.

Signed at Philadelphia, in the county of Philadelphia and State of Pennsylvania, this
25 seventh day of May, A. D. 1928.

GEORGE H. GIBSON.
